CLAIM

The ornamental design for a water sports equipment recreational device, as shown and described.

DESCRIPTION

1. Water sports equipment (recreational device)

1.1 : Perspective

1.2 : Bottom

1.3 : Back

1.4 : Right

1.5 : Front

1.6 : Left

1.7 : Top

The design shows a new, original and ornamental design for a water sports equipment (recreational device) as shown in the drawings; broken lines in the figures show portions of the water sports equipment (recreational device) that form no part of the claimed design.
